US00D907445S

(12) **United States Design Patent** (10) Patent No.: **US D907,445 S**
(45) Date of Patent: ** Jan. 12, 2021

(54)	CONTAINER ACCESSORIES	1,056,648 A	3/1913	Earley
(71)	Applicant: YETI Coolers, LLC , Austin, TX (US)	2,101,337 A	12/1937	Komenak
(72)	Inventors: Steve Charles Nichols , Austin, TX (US); Andy Bondhus , Austin, TX (US); Tobias Hotchkiss , Austin, TX (US); Mark Carlson Rane , Austin, TX (US); John Loudenslager , Austin, TX (US); Derek G. Sullivan , Austin, TX (US)	2,109,928 A	3/1938	Passalaqua
		2,439,660 A	4/1948	Rudolph
		2,472,491 A	6/1949	Bernard
		2,510,643 A	6/1950	Long
		2,565,939 A	8/1951	Wriston
		2,574,089 A	11/1951	Cochran
		2,577,951 A	12/1951	Johan
		2,581,417 A	1/1952	Cooley
		2,604,961 A	7/1952	Koch
		2,647,653 A	8/1953	Dube
		2,717,093 A	9/1955	Mautner
		2,747,732 A	5/1956	Fischer
		2,803,956 A	8/1957	Womer
		2,869,909 A	1/1959	Harling
		2,931,205 A	4/1960	Schmitz
		2,936,189 A	5/1960	Pearson
		3,057,636 A	10/1962	D'Ettorre et al.
		3,141,680 A	7/1964	McCord et al.
		3,191,244 A	6/1965	Burke
		3,202,310 A	8/1965	Tibbets
		3,225,983 A	12/1965	Majka
		3,250,558 A	5/1966	McClintock
		3,259,412 A	7/1966	Wheeler
		3,363,739 A	1/1968	Hodosh et al.
		3,416,701 A	12/1968	Kramer et al.
		3,432,025 A	3/1969	Luhe
		3,464,579 A	9/1969	Asenbauer
		3,565,305 A	2/1971	Belokin
		3,642,168 A	2/1972	Wiley, Jr. et al.
		3,656,650 A	4/1972	Frater
		3,661,410 A	5/1972	Larson et al.
		3,688,942 A	9/1972	Mitchell et al.
		3,690,708 A	9/1972	Worley et al.
		3,741,433 A	6/1973	Bentley et al.
		3,847,423 A	11/1974	Gley
		3,861,504 A	1/1975	McGraw
		3,882,914 A	5/1975	Strutz
		3,886,625 A	6/1975	Rollband
		3,902,628 A	9/1975	Schurman
		3,915,362 A	10/1975	Hart
		3,917,038 A	11/1975	Foge et al.
		3,933,269 A	1/1976	Mastrovito
		3,955,656 A	5/1976	Kashinski
		3,987,829 A	10/1976	Leone
		3,991,921 A	11/1976	Hirsch
		4,094,392 A	6/1978	Gregg et al.
		4,095,711 A	6/1978	Conley
		4,116,479 A	9/1978	Poe
		4,143,442 A	3/1979	Harlang
		4,153,178 A	5/1979	Weavers
		D256,630 S	9/1980	Maney

CLAIM

The ornamental design for container accessories, as shown and described.

DESCRIPTION

FIG. 1 is a top, front, left perspective view of container accessories showing our new design;

FIG. 2 is a front view thereof;

FIG. 3 is a top view thereof;

FIG. 4 is a right side view thereof;

FIG. 5 is a left side view thereof;

FIG. 6a is a top, front, left perspective exploded view of container accessories showing our new design;

FIG. 6b is a top, front, left perspective exploded view of an alternate configuration of container accessories showing our new design;

FIG. 7 is a top, front, left perspective view of an enlarged caddy accessory of container accessories showing our new design;

FIG. 8 is a bottom, rear, right perspective view thereof;

FIG. 9 is a front view thereof;

FIG. 10 is a rear view thereof;
FIG. 11 is a right side view thereof;
FIG. 12 is a left side view thereof;
FIG. 13 is a top view thereof;
FIG. 14 is a bottom view thereof;
FIG. 15 is a top, front, right perspective view of an enlarged divider accessory of container accessories showing our new design;
FIG. 16 is a bottom, rear, left perspective view of the divider thereof;
FIG. 17 is a front view thereof;
FIG. 18 is a rear view thereof;
FIG. 19 is a right side view thereof;
FIG. 20 is a left side view thereof;
FIG. 21 is a top view thereof;
FIG. 22 is a bottom view thereof;
FIG. 23 is a top, front, right perspective of an enlarged bag accessory of container accessories showing our new design;
FIG. 24 is a bottom, rear, left perspective view thereof;
FIG. 25 is a front view thereof;
FIG. 26 is a rear view thereof;
FIG. 27 is a left side view thereof;
FIG. 28 is a right side view thereof;
FIG. 29 is a top view thereof; and,
FIG. 30 is a bottom view thereof.

The even-length broken lines within the shaded area represent stitching.

FIGS. 7-30, showing the caddy, divider and bag accessory, are shown separate for clarity of illustration.
